UNITED STATES PATENT OFFICE.

FREDERICK W. LEWIS, OF PROVIDENCE, RHODE ISLAND, ASSIGNOR TO CHAPIN & HOLLISTER CO., OF PROVIDENCE, RHODE ISLAND, A CORPORATION OF RHODE ISLAND.

CHAIN.

1,405,851.

Specification of Letters Patent. Patented Feb. 7, 1922.

Application filed March 12, 1921. Serial No. 451,815.

To all whom it may concern:

Be it known that I, FREDERICK W. LEWIS, a citizen of the United States, residing at Providence, in the county of Providence and 5 State of Rhode Island, have invented certain new and useful Improvements in Chains, of which the following is a specification.

The invention relates primarily to chains, but it is especially adapted for use in the 10 jewelry art in the construction of bracelets, rings, necklace and the like.

The principal object of the invention is to provide a novel construction of chain in which the use of solder is obviated, and 15 which is capable of longitudinal flexibility. A further object of the invention is to provide a link consisting of a single piece of material, which obviates the use of independent connecting pins, screws or rivets.

20 Another object of the invention is to produce a chain which is inexpensive to manufacture and which is composed of a series of links which are so constructed as to enable them to be easily and quickly attached to or 25 removed from the chain.

To these ends the invention consists of the novel construction and arrangement of parts hereinafter described and more particularly set forth in the claims. In describing the 30 invention in detail, reference will be made to the accompanying drawings, in which—

Figure 1 is a top plan view of a portion of my improved chain.

Figure 2 is a side elevation.

35 Figure 3 is a bottom elevation.

Figure 4 is an enlarged longitudinal central section of two of the links.

Figures 5, 6, 7 and 8 are a plan view, a side view, an end view and a bottom view respectively of my novel form of link.

Figure 9 is a plan view of the under side of a plurality of links showing the bendable hinge-arms opened up on one link in position to enter the next adjacent link in assembling.

Referring to the drawings, my improved chain comprises a plurality of novel links 1, each of which consists of a substantially rectangular solid body portion. Each link 1 is provided at one end upon the bottom with two longitudinally extending lugs or arms 2, each of which has at its free end an inwardly extending hinge-member 3, as shown in Figure 1. Said hinge-members 3

are spaced from the end of the body portion and arranged above the plane of the bottom of the body portion, as shown in Figure 4. The bottom of the body portion 1 at the opposite end is cut away upon each side to form the recesses 4, which extend longitudinally and in alinement with the arms 2, as shown in Figure 9. These recesses are of a length and depth to receive the arms 2 of an adjacent link, so that when said arms engage 65 said recesses, the bottom surface of each lug will be flush with the bottom surface of the body portion. A hole 5 extends through the reduced body portion or remaining fin adjacent the inner end of the recesses 4 and is 70 of a size to freely receive the hinge members 3.

In assembling the links the lugs or arms 2 are spread apart, as shown in Figure 9, so as to enable the hinge-member 3 to straddle 75 the reduced part of the body portion between the recesses 4 and be inserted in the hole 5 in the body portion of the next adjacent link. When the free ends of said hinge-members 3 are brought into alinement with the hole 5 the arms 2 are closed, thereby forcing the hinge-members into the hole and pivotally joining the links to each other.

With the above construction it will be seen that the two hinge-members 3 form a split 85 hinge-member which can be quickly and easily opened up or closed for attaching or removing one link from another. It will also be seen that the links, being pivotally joined to each other transversely, are capable of assuming the positions shown in Figure 4, thereby giving to the chain a longitudinal flexibility.

By this construction it will be noted that the links are each swaged up complete of one 95 single piece of stock, and the different links may be connected up together by a single operation by simply bending inwardly the pair of arms of each link to pass its pivots into the openings of the next adjacent link.

100 By my particular arrangement of parts the joints between the links of the bracelet are practically closed and the same is very handsome and attractive in appearance.

I claim:

105 1. A chain link comprising a one piece body member provided at one end with a pair of integral bendable hinge arms having

inturned pivot ends and at its other end with an opening to receive the pivots carried by the arms of the next adjacent link.

2. An article of the character described, comprising a plurality of links, each consisting of a one part solid body portion provided at one end with a pair of integral bendable arms having inturned pivot ends, and at its opposite end with a transverse link-receiving hole.

3. An article of the character described, comprising a plurality of links, each link consisting of a body provided at one end with a pair of bendable arms each having an integral transverse hinge-member spaced from said body, the opposite end of said body being provided with a hole extending transversely through it at substantially the same distance from the opposite end as the width of the space between the hinge-member and the body.

4. An article of the character described comprising a plurality of links, each link consisting of a body, two bendable arms upon one end of the body a hinge-member formed integral with each of said arms and

the opposite end of said body being provided with a reduced portion or central fin having a transverse hole therethrough near its lower edge to receive said hinge members. 30

5. An article of the character described, comprising a plurality of links, each link consisting of a body, two lugs projecting longitudinally from one end of the body, each of said lugs being provided at its free end with a transverse hinge-member, two longitudinal channels at the opposite end of the body adapted to receive said lugs and a hole extending transversely through the body adapted to receive said hinge-members. 40

6. An article of the character described, comprising a plurality of links, each link consisting of a body, two lugs upon one end of the body and flush with the bottom thereof of a portion of a hinge-member formed integral with each of said lugs, two channels upon the opposite end of the body in longitudinal alinement with said lugs, and a hole adjacent the inner end of said channels and extending transversely through said body. 50

In testimony whereof I affix my signature.
FREDERICK W. LEWIS.
